UNITED STATES PATENT OFFICE.

EDWARD G. PETERSON, OF SOUTH RANGE, WISCONSIN.

SHOE-POLISHING DEVICE.

1,310,670.

Specification of Letters Patent. Patented July 22, 1919.

Application filed December 12, 1917. Serial No. 303,825.

To all whom it may concern:

Be it known that I, EDWARD G. PETERSON, a citizen of the United States, residing at South Range, in the county of Douglas and State of Wisconsin, have invented certain new and useful Improvements in Shoe-Polishing Devices, of which the following is a specification.

This invention relates to shoe polishing devices and more particularly to a fountain shoe brush adapted to contain a quantity of liquid shoe polish and provided with means for permitting a quantity of the liquid to be dispensed and received by the bristles of a polish applying brush in a manner that will permit the liquid to be applied to the shoe and spread thereover previous to polishing the same, which latter operation is accomplished through the medium of a polishing device forming a part of the invention and arranged to be conveniently manipulated by a handle common to both the polishing and the liquid applying elements.

One of the principal objects of the invention is to provide a fountain shoe brush of this character that may be held in a position for applying the liquid and permitting the liquid to flow through the applying brush and which will require but a single half turn in order to stop the flow of liquid for permitting the use of the polishing brush.

A further object of the invention is the provision of a device of this character which consists of comparatively few parts and simple in construction but durable and well adapted to withstand the rough usage to which devices of this character are ordinarily subjected.

For a full description of the invention and the advantages and merits thereof, reference is to be had to the following description and the accompanying drawings wherein is illustrated the preferred form of my invention, in which:

Figure 1 is a side elevation of the brush constructed in accordance with my invention.

Fig. 2 is an end elevation partly broken away to disclose the valve mechanism.

Fig. 3 is a fragmentary plan of a portion of the device partly broken away to disclose another view of the valve mechanism.

Referring to the drawings wherein is illustrated the preferred form of my invention in which, like numerals of reference indicate corresponding parts throughout the several

views, the handle 1 is preferably constructed of wood and is shaped from a block which is of rectangular formation whereby the body 2 of the brush is provided at one end of the handle when the latter has been properly shaped. It is my purpose to provide wood material for the reason that the body and handle may be readily and cheaply formed from this material and it will be light and durable when complete. In the end of the body 1 is drilled a longitudinal cylindrical recess 3 which may be of any desired length and preferably lined with tin or other similar material for preventing the contents from being absorbed by the wood body. This tin lining forms a receptacle for the liquid polish and the open end of the receptacle is closed by a removable cap 4 screw threaded mounted on the projected end of the tin lining for the opening. It will be observed in this connection that the tin lining may be in the form of a cylindrical container adapted to fit the opening or cylindrical recess 3 whereby the receptacle thus formed may be readily removed with the cover 4 attached if desired. In this manner the receptacle and the cover 4 may be independently manufactured and easily inserted in the opening provided in the wooden body 2.

Mounted on one side of the body is a circular base 5 having a plurality of brush bristles 6 attached thereto preferably in a series of tufts and the center of this disk 90 has a small opening communicating with a passage-way 7 in the body which establishes communication between the interior of the liquid container and the brush bristles so that when the brush is held with the bristles 6 extended downwardly the liquid will flow through the opening and profusely moisten the bristles 6. The opening in the disk 5 and the body of the receptacle are aligned with a cylindrical sleeve 8 of metal whereby the liquid flowing through the opening will not be absorbed by the wooden body or disk 5. Extending laterally through a screw threaded opening in the body is a valve stem 9 which is also screw threaded and has a thumb nut or handle 10 on its outer end whereby it may be manipulated to open and close the passage-way for regulating the flow of liquid to the bristles.

Attached to the opposite side of the body 110 is a polishing brush 11 which may consist of a piece of wooden fabric or similar material

best adapted for polishing the shoe leather after the liquid shoe polish has been applied thereto.

In use, the cover 4 will first be removed, 5 or the interior receptacle may be entirely removed from the body and filled with the liquid polish after which it will be replaced and the cover 4 tightly fixed in position. Then by opening the valve by turning the 10 thumb nut 10 the liquid will flow from the container to the bristles 6 to profusely saturate the bristles whereby they may be employed to apply the liquid to the surface of the shoe. When sufficient liquid has been 15 applied to the surface of the leather of the shoe, the device may be simply given a half turn that is inverted until the bristles are disposed upwardly and the polishing process through the medium of the polishing element 11 may immediately proceed, even before the valve is turned off.

From the foregoing it will be observed that a simple and durable shoe polishing brush has been provided the details of which 25 embody the preferred form. I desire it to be understood, however, that slight changes in the minor details of construction may be

made without departing from the spirit of the invention or the scope of the claim hereunto appended.

30

I claim.

A shoe polishing brush comprising a brush body, a removable receptacle mounted in the body, the latter being provided with a removable tube extending into and communicating with the said receptacle approximately intermediate its ends in order that the contents of the receptacle may be passed into the said tube, a valve transversely mounted in the body of the brush and adapted to extend into and close the passage-way in the said tube, a removable bristle carrying member mounted on the body and having an opening to receive the outer end of the said tube whereby the contents of the 40 said receptacle may be received on the bristles when the said valve is moved to open position.

35

In testimony whereof I affix my signature in presence of two witnesses.

EDWARD G. PETERSON.
